UNITED STATES PATENT OFFICE.

ARTHUR M. SMITH, OF SAN FRANCISCO, CALIFORNIA, ASSIGNOR TO MARSHALL & STEARNS COMPANY, OF SAN FRANCISCO, CALIFORNIA, A CORPORATION OF CALIFORNIA.

RISER.

Application filed May 31, 1922. Serial No. 564,754.

To all whom it may concern:

Be it known that I, ARTHUR M. SMITH, a citizen of the United States, residing at the city and county of San Francisco and State 5 of California, have invented new and useful Improvements in Risers, of which the following is a specification.

This invention relates to a riser for use in bed structures.

10 The object of the invention is to simplify and improve the construction and operation of a device of this character. In carrying out this object I make use of a sheet metal riser detachably fitted upon the side rail of 15 the bed structure and extending upwardly to form a support for the transverse rail to which the spring fabric is secured. The riser is of simple and inexpensive construction and is readily and easily attached to the side 20 rail and permits the anchor rail to be quickly and easily attached thereto. The riser, while constructed of comparatively thin material, is so shaped as to afford ample support and resistance to the weight imposed thereon by 25 the spring fabric. A novel and inexpensive way of securing the head piece to the riser is also embodied in the present invention.

One form which my invention may assume is exemplified in the following description 30 and illustrated in the accompanying drawings, in which—

Fig. 1 shows a side elevation of a folding bed fitted at each end with a riser built in accordance with my invention.

35 Fig. 2 shows a side elevation of a part of the head of the bed.

Fig. 3 shows a rear elevation of the part shown in Fig. 2.

40 Fig. 4 shows a plan view of the sheet of material from which the riser is constructed.

In the present form of the device a side rail 10 is fitted at each end with a riser 11. On the top of each riser is an angle bar 12 which serves as an anchor for spring fabric 45 13. In the structure shown, the outer end of the frame is supported by a foldable foot piece 14 and the inner end carries a jointed head piece consisting of a lower stationary tubular member 15 and a hinged upper portion 16.

50 The head of the bed frame is pivotally mounted upon brackets 17 for folding movement. It is obvious, however, that the riser with which the present invention is particularly concerned may also be used in

connection with beds other than folding beds. 55

The riser consists of a piece of sheet metal in the form shown in Fig. 4 having a body portion 18 and legs 19. The body portion is bent into the shape of a U, considered in plan, and the legs are made to encompass 60 the side rail. The ends of the legs have tabs 20 to enter a slot 21 in the bottom of the side rail and prevent spreading of the side walls and to retain the riser in place. A riser is thus formed which is anchored at its 65 lower portion and has a vertical flat wall at each side and a convex wall at the end disposed towards the spring fabric. This convex wall will serve to resist endwise the load imposed thereon by the spring fabric. The 70 outer end of the riser is left open. The edge of each side wall at the open end has a lug 22 to enter an opening in the anchor rail 12 for retaining the latter in place.

On one of the side walls, near the bottom 75 thereof, is an elongated tab 23 adapted to be extended across the open face of the riser and to receive a bolt 24 for fastening the lower end of the stationary tubular member 15 in position thereon. This tubular member 80 is also connected to the anchor rail 12 by means of a bolt 25 which extends through said tubular member and has its head lying in a slot 26 formed in the said anchor rail. The slot in the anchor rail permits the bolt 85 25 to be arranged on the tubular member before the parts are assembled and the bolt can thereafter be tightened by means of a nut 27 disposed at the outside of the tubular member. The position of the bolt 24 is such 90 as to permit of its being inserted and connected up after the parts are assembled.

Access to one end of the bolt 24 may be had through the open end of the tubular member 15, whereas the other end of the 95 bolt is accessible through the open face of the riser. If this bolt were accessible only through the open end of the tubular member 15, then it would be necessary to tap it onto the riser, which would require a heavier piece of metal than that from which the riser is made, thus making it impossible to use the integral arrangement shown at 23.

Various changes in the construction and arrangement of the several parts herein 100 shown and described may be employed without departing from the spirit of my invention as disclosed in the appended claims.

Having thus described my invention, what I claim and desire to secure by Letters Patent is:—

1. In a bed structure, a side rail, a sheet metal riser having its body portion bent into the form of U when viewed in plan, legs integral with the body portion and extending around the rail, the ends of said legs being inturned to engage the sides of a slot 10 formed in the rail.
2. In a bed structure, a side rail, a sheet metal riser comprising a body portion U-shaped in plan, legs formed integrally with the side walls of the riser extending 15 around the side rail and angular portions on the ends of the legs adapted to enter a slot in the bottom of the side rail.
3. In a bed structure, a side rail, a sheet metal riser comprising a body portion 20 U-shaped in plan, legs forming a continuation of the side walls of the U-shaped structure extending around the side rail, means

for detachably securing the ends of the legs in a slot formed in the rail and an anchor rail for supporting the spring fabric arranged upon said riser, said riser having the convex portion of the U-shaped structure disposed between the anchor rail and side rail so as to resist endwise the tension of the spring fabric. 25 30

4. In a bed structure, a side rail, a sheet metal riser comprising a body portion U-shaped in plan disposed above the rail, the side walls of the body portion being extended around the rail, an anchor rail for the spring fabric carried on the U-shaped structure, a tab formed integrally with one of the side walls and extending across the open face of the U-shaped structure, a post adjacent the open face of the riser and 35 means connected with the tab and the anchor rail for securing the post in position. 40

ARTHUR M. SMITH.
